(57) **CLAIM**

The ornamental design for a skin toning device, as shown and described.

DESCRIPTION

FIG. 1 is a front perspective view of a skin toning device; FIG. 2 is a rear perspective view of the skin toning device shown in FIG. 1;

FIG. 3 is a front elevational view of the skin toning device shown in FIG. 1;

FIG. 4 is a rear elevational view of the skin toning device shown in FIG. 1;

FIG. 5 is a right side elevational view of the skin toning device shown in FIG. 1;

FIG. 6 is a left side elevational view of the skin toning device shown in FIG. 1;

FIG. 7 is a top plan view of the skin toning device shown in FIG. 1; and,

FIG. 8 is a bottom plan view of the skin toning device shown in FIG. 1.

In the drawings, the dashed broken lines represent features that form no part of the claimed design.
